US00D950858S

(12) **United States Design Patent** (10) **Patent No.:** **US D950,858 S**
(45) **Date of Patent:** **** May 3, 2022**

(54) **SMART FEEDER**

(71) Applicant: **Xiaoyi Intelligent Technology Yangzhou Co., Ltd.**, Yangzhou (CN)

(72) Inventor: **Yuan Gong**, Yangzhou (CN)

(73) Assignee: **Xiaoyi Intelligent Technology Yangzhou Co., Ltd.**, Yangzhou (CN)

(**) Term: **15 Years**

(21) Appl. No.: **29/794,013**

(22) Filed: **Jun. 9, 2021**

(30) **Foreign Application Priority Data**

Dec. 16, 2020 (CN) 202030776124.5

(51) **LOC (13) Cl.** **30-07**

(52) **U.S. Cl.**

USPC **D30/122**

(58) **Field of Classification Search**

USPC ..... CLAIM

The ornamental design for a smart feeder, as shown and described.

DESCRIPTION

FIG. 1 is a top, front and right perspective view of a smart feeder showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the figures illustrate portions of the smart feeder that form no part of the claimed design.

1 Claim, 7 Drawing Sheets
